UNITED STATES PATENT OFFICE.

MERRILL G. BARKER, OF NORWALK, CONNECTICUT, ASSIGNEE TO THE BARKER FACTORY, INC., OF NORWALK, CONNECTICUT, A CORPORATION OF CONNECTICUT.

MARINE ENGINE.

Application filed October 23, 1924. Serial No. 745,381.

This invention, while relating generally to marine motors, is more particularly concerned with the conversion of automotive engines to marine use by application thereto of special devices adapting it to the somewhat dissimilar requirements of such service. For instance, motors for Ford cars if adapted to marine purposes might be found economical for the propulsion of small types of boats. Accordingly, the improvements herein are described with particular reference to their incorporation in Ford motors.

It is the principal object of the invention to provide means of inexpensive and simple type, for associating with a Ford motor a water cooling system which shall include a water pump whereby the motor shall be more rapidly cooled and its working capacity increased as necessary for marine uses. Still another object is to mount such a water pump in an accessible position at the front end of a Ford motor and to remount the standard timer so as to afford space for the water pump. A further object of the invention is to connect both the water pump and the timer to the cam shaft by means which are simple and shall insure against the improper timing of the distributor.

In furtherance of the general objects of the invention, other features of the improved cooling system are involved and a remounting of the propeller shaft is made to afford the greater degree of angularity therefor encountered in a boat and to resist the axial thrust placed thereon by the churning propeller. In carrying out these objects means are provided which not only provide for the necessary angularity but also for the absorption of the thrust and the retention of oil within the transmission housing with the exclusion of dirt and water therefrom.

These and other objects will appear at greater length in connection with the detailed description of the embodiment illustrated in the accompanying drawings, wherein:

Figure 1 is a view in side elevation showing a Ford type motor having the improvements associated therewith to adapt it for marine purposes.

Figure 2 is a view in front elevation thereof illustrating particularly the mounting of the water pump and distributor, the cap of the distributor being broken away.

Figure 3 is a detail view partly in side

elevation and partly in section of the water pump and distributor and showing particularly the driving connections between these units and the cam shaft.

Figure 4 is a fragmentary view, partly in plan and partly in horizontal section, showing the universal connection between the propeller shaft and transmission housing.

As the description proceeds it will appear that some features of the invention may be useful in adapting other types of motor than the Ford to marine usage and for that reason the drawings illustrate the engine itself very conventionally although the front and rear ends correspond to those of a Ford motor. Such a motor as *a* has at its front end a timing gear cover *b* through which extends forwardly a cam shaft *c* which ordinarily carries directly thereon a timer such as *d*. The cooling of such motor is ordinarily accomplished by a thermo-siphon system in which no pump is employed. For marine purposes it is believed desirable to increase the capacity of the cooling system by incorporating therein a water pump *e* which may take water from outboard and discharge it into the exhaust after passing through the engine jacket. It is proposed in accordance with the present invention to remount the distributor *d* at one side of the cam shaft *c* so as to afford space for the water pump *e* and permit both the pump and distributor to be driven from the shaft *c*. To accomplish this by simple and accessible means which may be readily assembled, it is proposed to provide a bracket *f* which is bolted to the plate *b* by long bolts *g* entering the same bolt holes which are found in standard parts. The pump *e* is mounted at the forward end of the bracket *f* with its rotor connection centered with respect to the shaft *c*. This rotor connection is illustrated as a rod *e'* which enters a sleeve *h* and is pinned thereto as at *h'*, this sleeve being fitted onto the end of the cam shaft *c* and driven therefrom by a driving pin *h''*. The end *h'''* of the driving pin *h''* is of reduced diameter and enters loosely a recess *c'* within the shaft *c*. The looseness of the fit of the shaft *c* in the sleeve *h* and of the reduced end *h'''* of the driving pin in the recess *c'* facilitates assembling and compensates for any slight angular or linear misalignment of the shaft *c* with the shaft *e'*.

An intake pipe *e''* is provided at one side of

the gear pump e while the outlet side is connected through a hose e^3 with the jacket of the motor, the circulatory system of which terminates in a hose connection a' leading to the exhaust pipe a^2 in a manner which will be evident.

The distributor d is mounted on an arm f' of the bracket f and is provided with a shaft d^2 extending at right angles to the shaft c and the driving connection therefor is afforded through a bevel gear d' at the lower end of a shaft d^2 for the distributor and a similar bevel gear i which meshes therewith and is slipped onto the sleeve h and pinned thereon by the same driving pin h^2 which engages the sleeve. The aligned openings tapped in the hub of the gear i and in the sleeve h are tapered slightly so that when the driving pin is threaded therein it sets up tight in the threads with the reduced end h^3 in predetermined relation to the bottom of the recess c' . The assembly of the parts described is made with the proper meshing of the teeth of the gears i and d' to insure correct timing. All of the parts are accessible and simple and their mounting and demounting may be readily accomplished through the bolts g for the bracket f .

In further adapting the motor to marine purposes it will be found that the propeller shaft k ordinarily would require considerably more angularity than is present in automotive work. It is a further object of the present invention to provide means whereby such angularity will be afforded through the connection with the transmission housing a^3 of the engine as shall effectively retain grease within the housing and exclude water and dirt therefrom. This improved connection, as will be described, is also of such character as to absorb axial thrust impressed on the shaft by the propeller k^2 . The propeller shaft k receives power through a universal joint h^2 from the engine shaft. A sleeve l affords a bearing for the shaft k beyond the universal joint h^2 and has a

spherical end l' which is secured within the transmission casing a^3 in any desired angular position by means of retaining rings m , m' , of generally spherical form which are bolted onto the casing by bolts n . Obviously, the angular position of the shaft k may be adjusted as desired by the means described. In boat structures the shaft k must be journaled fixedly in position adjacent its ends. The improved ring structure serves the dual function of affording an inboard bearing for the inner end of the sleeve l thereby holding the shaft k in proper alignment and also affording the necessary capacity for angularity in assembling. A packing strip o may be interposed between the spherical end l' of the sleeve and one of the spherical rings m' to retain grease and exclude water and foreign substances. The sleeve l may also be used as a thrust member by pinning a collar p on the shaft k in proximity to the outer end of the sleeve and interposing, if desired, an annular thrust bearing p' between the collar and sleeve. The thrust reaction is, of course, eventually taken by the transmission casing a^3 as is desirable.

The improvements herein may be modified in structural details and in the particular arrangement of parts illustrated without avoiding the spirit of the invention which is recited in more general terms in the appended claim.

What I claim is:

In combination with an internal combustion engine having a protruding shaft driven from the engine, a water pump mounted with its rotor aligned with the shaft, a driving sleeve connection pinned to the rotor operatively and to the shaft, a distributor mounted at one side of the shaft, and a driving gear for the distributor mounted on the said sleeve and secured to the shaft by the said pinning means.

This specification signed this 20th day of October A. D. 1924.

MERRILL G. BARKER.
